UNITED STATES PATENT OFFICE.

EVERETTE C. CONRADE, OF LEWISVILLE, NORTH CAROLINA.

SHUTTER OPERATING AND SECURING MECHANISM.

Application filed April 14, 1922. Serial No. 552,653.

To all whom it may concern:

Be it known that I, EVERETTE C. CONRADE, a citizen of the United States, residing at Lewisville, in the county of Forsyth and 5 State of North Carolina, have invented new and useful Improvements in Shutter Operating and Securing Mechanism, of which the following is a specification.

The object of my present invention is the 10 provision of simple, easily-operated and efficient means through the medium of which shutters may be opened and closed and secured in closed and open positions from a point within a room and without raising a 15 window sash.

To the attainment of the foregoing, the invention consists in the improvement as hereinafter described and definitely claimed.

In the accompanying drawings, forming 20 part of this specification:—

Figure 1 is a fragmentary elevation with the door of the cabinet in open position.

Figure 2 is an elevation of portions of 25 shutters and certain elements of my improvement.

Figure 3 is an enlarged horizontal section on the line 3—3 of Figure 1, showing the parts of my improvement in the positions they occupy when the shutters are closed as 30 indicated by dotted lines.

Figure 4 is a similar view with the shutters secured in open position.

Figure 5 is an enlarged detail vertical section taken in the plane indicated by the 35 line 5—5 of Figure 2.

Figure 6 is an enlarged detail horizontal section taken on the line 6—6 of Figure 2.

Figure 7 is a detail vertical section showing the locking of the shutters in closed 40 position.

Figures 8 and 9 are detail vertical sections hereinafter specifically referred to; Figure 8 being taken on the line 8—8 of Figure 4, looking inwardly, and Figure 9 45 being taken on the line 9—9 of Figure 4, looking outwardly.

Figure 10 is an enlarged sectional view of one of the operating rods.

Figure 11 is an enlarged perspective of 50 one of the arms on said shaft.

Figure 12 is an enlarged plan view of one of the shutter pinions.

Similar numerals of reference designate 55 corresponding parts in all of the views of the drawings.

The window casing, the sashes and the shutters are, in general, of the ordinary well known construction, the shutters being designated by the numerals 4 and 5. It will be noted, however, Figure 7, that the outer 60 shutter 5 which is adapted when closed to overlap the shutter 4, is provided in its lower end with a socket 6; also, that the pintles 7 of the lower hinges of the shutters 4 and 5 are utilized as journals for pinions 8. Figures (2, 5, 6 and 12) on which are bifurcated portions 9 that straddle the hinge members 10 fixed to the shutters 4 and 5 so that swinging of the said shutters 4 and 5 65 will cause turning of the pintles 8. 70

Intermeshed with the pinions 8 are horizontal sector-gears 11 on upright shafts 12 which are provided at their lower ends with gears 13, Figures (3, 4 and 5). The said gears 13 are meshed with sector-gears 14 75 forming the outer arms of horizontal levers, fulcrumed at 15, and provided with inner arms 16.

Appropriately secured in the base portion 80 of the window casing at the inner side thereof is a cabinet body 17, Figures (1, 3 and 4), having a hinged door 18 on which is a fastener 19 to detachably secure it in closed position.

Guided in the inner wall 20 of the casing 85 body 17 are shutter-operating rods 21, pivotally connected at 22 to the levers 16 and having handles or finger pieces 23. Each of the said rods is preferably formed of telescopic sections 24 and 25, adjustably fixed 90 to each other by a set screw 26. From this it follows that said rods may be increased or diminished in length to suit the thickness of the window casing to which my improvement is applied. 95

It will be apparent from the foregoing that when the shutters 4 and 5 are unlocked, outward thrust of the rods 21, positioned as shown in (Figure 3), will bring about opening of the shutters 4 and 5, while inward pull on the rods 21, positioned as in (Figure 4), will cause closing of the shutters 4 and 5, the shutter 5 being opened first and closed last.

Carried by the rods 21 and preferably 105 fixed to the sections 24 thereof are arms 27, (Figures 3, 4, 9 and 11).

At 28 is a vertical sleeve in the base portion of the window casing, and at 29 is a vertically-movable bolt, guided in the sleeve 110

28 and adapted to enter the socket 6 when the outer shutter 5 is in closed position, (Figure 7.) The said bolt 29 is provided with arms 30 and 31, and a retractile spring 5 32 is connected to the arm 31, and tends to retract the bolt and release the shutter 5. A horizontal rock shaft 33 is journaled in the wall 20 of the cabinet body 17 and in a fixed bearing 34 arranged in the outer 10 portion of the window casing 1, (Figures 3 and 7.) Said shaft 33 is provided within the cabinet body 17 with a handle 35, (Figures 1, 3 and 4.) At its outer end the shaft 33 has fixed thereto an arm or disk 15 36 on which is a stud 37 that rests under and in engagement with the arm 30 on the shutter locking bolt 29. Thus when the handle 35 is in the position shown in (Figures 1 and 3), the bolt 29 will be secured 20 against downward movement and the shutter 5 will be locked in closed position. When, however, the handle 35 is turned through a quarter of a revolution as indicated by dotted lines in (Figure 1), it will 25 be noted that the spring 32 will be enabled to retract the bolt 29 and release the shutter 5.

As before indicated outward thrust of the rods 21 to the positions shown in (Figure 30 4) is necessary for the opening of the shutters 4 and 5.

For the purpose of locking and securing the shutters in open position I provide the rock shaft 40 (Figures 3, 4, 8 and 9) with 35 a handle 41 in the cabinet body 17 and with an arm 42 against the outer side of the wall 20 and adapted to be engaged against stops 43 and 44 on said wall 20. The outer end of the shaft 40 is journaled in an appropriately fixed bearing 45, (Figures 3 and 4), and near said bearing the shaft 40 has fixed thereto a plate 46, (Figures 3, 4 and 9.) Manifestly when the arms 27 are located as in (Figure 4), the shutters 4 and 5 being 45 open, and the shaft 40 is turned about its axis to arrange the plate 46 as shown in Figure 10 relatively to the arms 27, the plate will prevent inward movement of the arms 27 and hence the shutters 4 and 5 cannot close. When, however, the shaft 40 is 50 rocked to carry the arm 42 from the stop 43 to the stop 44, (Figure 8), the plate 46 will be positioned to clear the arms 27, and the shutters 4 and 5 can then be closed by 55 inward pull on the rods 21.

It will be readily understood from the foregoing that all of the manipulations described can be made from within a room without the necessity of raising the lower 60 sash of the window.

I have entered into a detailed description of the construction and relative arrangement of the parts embraced in the present and preferred embodiment of my invention 65 in order to impart a full, clear and exact

understanding of the said embodiment. I do not desire, however, to be understood as confining myself to the said specific construction and relative arrangement of parts inasmuch as in the future practice of the 70 invention various changes and modifications may be made such as fall within the scope of my invention as defined in my appended claims.

Having described my invention, what I 75 claim and desire to secure by Letters-Patent, is:—

1. The combination of a window casing, shutters hinged thereto, pinions carried by the pintles of the hinges and fixed to the 80 shutters, upright shafts having upper and lower gears, the upper gears meshed with said pinions, and levers fulcrumed in the base portion of the window casing and having gears on their outer arms meshed with 85 the lower gears of the upright shafts.

2. The combination of a window casing, shutters hinged thereto, pinions carried by the pintles of the hinges and fixed to the 90 shutters, upright shafts having upper and lower gears, the upper gears meshed with said pinions, and levers fulcrumed in the base portion of the window casing and having gears on their outer arms meshed with 95 the lower gears of the upright shafts, the said pinions on the hinge pintles having bifurcated portions receiving the shutter members of the hinges to fix the pinions to the shutters.

3. The combination of a window casing, 100 shutters hinged thereto, pinions carried by the pintles of the hinges and fixed to the shutters, upright shafts having upper and lower gears, the upper gears meshed with said pinions, and levers fulcrumed in the 105 base portion of the window casing and having gears on their outer arms meshed with the lower gears of the upright shafts, with push and pull rods guided in the base portion of the window casing and connected 110 with the inner arms of the levers, arms in said rods, and adjustable means adapted in one position to cooperate with said arms in preventing inward movement of the rods and casual closing of the shutters.

4. The combination of a window casing, 115 shutters hinged thereto, pinions carried by the pintles of the hinges and fixed to the shutters, upright shafts having upper and lower gears, the upper gears meshed with 120 said pinions, and levers fulcrumed in the base portion of the window casing and having gears on their outer arms meshed with the lower gears of the upright shafts, with push and pull rods guided in the base portion of the window casing and connected 125 with the inner arms of the levers, arms in said rods, and adjustable means adapted in one position to cooperate with said arms in preventing inward movement of the rods 130

and casual closing of the shutters, the said push and pull rods being adjustable as to length.

5. The combination of a window casing, shutters hinged thereto, pinions carried by the pintles of the hinges and fixed to the shutters, upright shafts having upper and lower gears, the upper gears meshed with said pinions, and levers fulcrumed in the 10 casing portion of the window casing and having gears on their outer arms meshed with the lower gears of the upright shafts, with push and pull rods guided in the base portion of the window casing and connected 15 with the inner arms of the levers, arms in said rods, and adjustable means adapted in one position to cooperate with said arms in preventing inward movement of the rods and casual closing of the shutters, said adjustable 20 means including a rock shaft having a handle and also having a plate arranged to be swung into and out of the path of inward movement of the arms.

6. The combination of a window casing, 25 shutters hinged thereto, pinions carried by the pintles of the hinges and fixed to the shutters, upright shafts having upper and lower gears, the upper gears meshed with said pinions, and levers fulcrumed in the 30 casing portion of the window casing and having gears on their outer arms meshed with the lower gears of the upright shafts, with push and pull rods guided in the base portion of the window casing and connected 35 with the inner arms of the levers, arms in said rods, and adjustable means adapted in one position to cooperate with said arms in preventing inward movement of the rods and casual closing of the shutters, said adjustable 40 means including a rock shaft hav-

ing a handle and also having a plate arranged to be swung into and out of the path of inward movement of the arms, and the push and pull rods and the rock shaft extending into a cabinet in the base portion 45 of the window casing.

7. The combination of a window casing, shutters hinged thereto, pinions carried by the pintles of the hinges are fixed to the shutters, upright shafts having upper and 50 lower gears, the upper gears meshed with said pinions, and levers fulcrumed in the base portion of the window casing and having gears on their outer arms meshed with the lower gears of the upright shafts, with a 55 bolt to lock the outer shutter, a spring to retract said bolt, and a shaft in the lower portion of the window casing having a handle and also having an arm and means on the arm to engage the bolt with the outer 60 shutter.

8. The combination of a window casing, shutters hinged thereto, pinions carried by the pintles of the hinges and fixed to the shutters, upright shafts having upper and 65 lower gears, the upper gears meshed with said pinions, and levers fulcrumed in the base portion of the window casing and having gears on their outer arms meshed with the lower gears of the upright shafts, with a 70 bolt to lock the outer shutter, a spring to retract said bolt, and a shaft in the lower portion of the window casing having a handle and also having an arm and means on the arm to engage the bolt with the outer 75 shutter, the handle portion of the shaft being disposed in a cabinet in the lower or base portion of the window casing.

In testimony whereof, I affix my signature.
EVERETTE C. CONRADE.
